[57] CLAIM

The ornamental design for a shelf bracket, as shown and
described.

DESCRIPTION

FIG. 1 is a left end, partial top and front perspective
view of a shelf bracket showing my new design;
FIGS. 2 and 3 are respectively top and bottom plan
views thereof;
FIGS. 4 and 5 are respectively front and rear eleva-
tional views thereof; and
FIG. 6 is a right end elevational view thereof.
